DESIGN FOR A COLORIMETER

William H. Harrison, Los Angeles, Calif.

Application January 2, 1946, Serial No. 125,238

Term of patent 14 years

(Cl. D61—1)

To all whom it may concern:

Be it known that I, William H. Harrison, a citizen of the United States, residing in the city of Los Angeles, in the county of Los Angeles, State of California, have invented a new, original, and ornamental Design for a Colorimeter, of which the following is a specification, reference being had to the accompanying drawing, forming a part thereof.

Fig. 1 is a front elevational view of a colorimeter showing my new design,

Fig. 2 is a side elevational view thereof, and

Fig. 3 is a rear elevational view of the colorimeter on a slightly reduced scale.

I claim:

The ornamental design for a colorimeter, substantially as shown and described.

WILLIAM H. HARRISON.
